HIS ATTORNEY

UNITED STATES PATENT OFFICE.

OSCAR G. H. KALLENBACH, OF ROCHESTER, NEW YORK, ASSIGNOR TO BAUSCH & LOMB OPTICAL COMPANY, OF ROCHESTER, NEW YORK, A CORPORATION OF NEW YORK.

PROTECTOR FOR VISION-APERTURES OF MARINE VESSELS.

1,335,059.

Specification of Letters Patent. Patented Mar. 30, 1920.

Application filed October 9, 1919. Serial No. 329,527.

To all whom it may concern:

Be it known that I, OSCAR G. H. KALLENBACH, a citizen of the United States, residing at Rochester, in the county of Monroe and 5 State of New York, have invented certain new and useful Improvements in Protectors for Vision-Apertures of Marine Vessels; and I do hereby declare the following to be a full, clear, and exact description of the same, 10 reference being had to the accompanying drawings, forming a part of this specification, and to the reference-numerals marked thereon.

My present invention relates to means for 15 preventing the obscuration of vision through vision apertures of marine vessels by waves or spray rising from the surface of the water and is adapted particularly for use in connection with such devices as submarine perisopes, when the vessels carrying them are 20 submerged with the periscope only above the surface of the water. To this end the invention consists generally in the provision of a deflector so arranged relatively to the 25 aperture to be protected, that spray or waves rising from the surface of the water and particularly those caused by the movement of the support, such as a periscope tube, through the water in the direction of the 30 vision aperture, will be deflected away from the glass or objective in order to prevent obscuration of vision, all as will be herein-after described and pointed out in the claims at the end of the specification.

35 In the accompanying drawings:

Figures 1, 2 and 3 are perspective views showing the aperture of the periscope with my invention applied thereto, showing the manner of deflecting the water caused by its 40 movement relative to the tube.

Fig. 4 is a horizontal sectional view taken on the line $x-x$ of Fig. 5 looking upward.

Fig. 5 is a vertical sectional view through the deflector, the periscope tube being shown 45 partially in elevation.

Fig. 6 is a perspective view of the device applied to a periscope and Fig. 7 a similar view of a modification.

Similar reference numerals indicate similar parts.

While the invention is particularly adapted to use in connection with submarine periscopes and I have shown it in this

connection, it may in its broader aspects be adapted to other uses.

1 indicates an ordinary periscope tube having at its upper end a substantially horizontal opening containing a glass window which may be plane or lenticular in form and presented normally forwardly or in the direction of motion of the vessel. Arranged directly beneath this window or aperture is a deflector composed in the present instance of a member or block 3 preferably of metal embodying a ledge with its lower portion 65 substantially triangular and provided with curved deflecting surfaces 4 extending from the forward and lateral edges downwardly and inwardly to the point 5, these surfaces being so formed that water or spray rising 70 from the surface of the water will be deflected away from the window particularly when the periscope is moving relatively forwardly as shown more particularly in Figs. 1 to 3 inclusive. In the present embodiment 75 this deflector is composed of a cast metal block secured in position by a band 6 extending around the periscope tube its forwardly extending ends being clamped by nuts 7 to a block 8 arranged between them. The block 80 is provided with a threaded aperture to receive the inner end of a bolt 9 passing through it as shown in Figs. 4 and 5 and is thereby removably secured thereto, but, of course, any other suitable form of connection could be employed without departing 85 from my invention. The surface 10 of the deflector is preferably inclined slightly downwardly in order that it may readily shed water.

90 The particular form of the device shown is readily applicable to the periscope tube of the ordinary construction.

In the form illustrated in Fig. 7 the block 95 is shown as attached to the periscope tube by other means than the detachable band connection, as for instance, by making it an integral part of the tube.

I claim as my invention:

1. A deflector for protecting vision apertures in marine vessels, the same comprising an outwardly extending ledge arranged beneath said aperture having its under surface tapering inwardly and downwardly from its ends and forward edge toward a substantially central point.

2. A deflector for protecting vision apertures in submarine periscope tubes, the same comprising an outwardly extending ledge arranged beneath the vision aperture of the periscope tube having its under surface inclined downwardly and inwardly from the outer and forward edges thereof toward the tube body.
3. A deflector for protecting vision apertures in submarine periscope tubes, the same comprising an outwardly extending ledge arranged beneath the vision aperture having its upper side downwardly inclined toward

the front edge and its undersurface downwardly inclined toward the tube body from 15 its outer and forward edges.

4. A deflector for protecting vision apertures in submarine periscope tubes, the same comprising a member having a ledge and its under surface inclined downwardly from 20 the forward and side edges toward the center, a securing band encircling the tube and means for attaching said member to the band with the ledge beneath the vision aperture.

OSCAR G. H. KALLENBACH.
